UNITED STATES PATENT OFFICE

CHARLES PASCAL, OF MONTREAL, QUEBEC, CANADA, ASSIGNOR TO PASCAL RAIL JOINT COMPANY, INC., A CORPORATION OF NEW YORK

ELECTRIC CONTACT IN RAIL JOINTS

Application filed August 30, 1922. Serial No. 585,257.

The invention relates to electric contact in rail joints as described in the present specification and illustrated in the accompanying drawings that form part of this application.

5 The invention consists essentially in the construction, combination and arrangement of parts hereinafter more fully described and claimed, and illustrated in the accompanying drawings.

10 The objects of the invention are to furnish in electrically connected rail lines contact members of higher conductivity than the rail metal thereby insuring a safe and positive electrical connection in rail joints, and to effect improvement in my pending application for electric connector in rail chair, Serial 569,106, filed June 17th, 1922.

In the drawings, Figure 1 is a perspective view of a rail joint showing the rail in cross section and broken away to disclose the contact members.

Figure 2 is a perspective detail of a base connector lower plate.

25 Figure 3 is a perspective detail of a base connector upper plate.

Figure 4 is a perspective detail of a base connector side strip.

30 Figure 5 is a cross sectional view showing a section of rail base, copper contact member, and base connector side strip.

Like numerals of reference indicate corresponding parts in the various figures.

Referring to the drawings, the rail joint is formed on the base plate 11^a having the rail recess 13 between the recess 14 and abutment 15. The copper plate conductor 16 is laid on the base plate 11^a. The bases 3 and 4 of the rails 1 and 2 are drilled at 5, 6, 7 and 8 and the rails are then placed on the copper plate 16 and the copper contact members, or plugs 9, 10, 11 and 12 are inserted in the holes 5, 6, 7 and 8 and hammered to a tight fit. The copper plate 17 is then laid on the upper side of the base to one side of the web and over the copper contact members 9 and 10. The side strip 18 of copper is inserted in the bed of the recess 14 and over the copper contact members 11 and 12. The copper contact members 9, 10, 11 and 12 thereby make electrical contact with the copper plate 16 under

the base of the rail, the upper plate 17, and the copper side strip 18.

The joint plate 19 fits against the rail and extends outwardly over the rail base and base abutment and completely covers the copper plate therebelow and the bolts 20 and the nuts 21 fasten the said joint plate and copper conductor to the base 11^a, as well as closing in the filler key 22.

In the use of this invention, the copper contact members are inserted in the holes drilled in the rail bases and swelled with a hammer to a tight fit, and in the installation of the rail joint they are bridged from rail to rail by the copper plate connector under the rail base, by the copper side strip, and by the copper upper connector over the rail base, the whole being drawn tightly together by the nuts and bolts through the joint plate. There is thus secured a reliable and positive electrical connection from rail to rail.

It is to be distinctly understood that the form and shape of contact member illustrated and described is the preferred form of the invention, but the applicant does not restrict himself to this one form or shape, as these copper contact members may be made in any other suitable shape and inserted in holes in the rails, base or web.

What I claim is:

1. In a rail joint, the combination with adjacent rail ends of a rail chair securing the rail ends in place, the rail base flanges at one side having openings therein merging with the outer edges of said rail base flanges, plugs of high electrical conductivity swelled into said openings, and a strip of high electrical conductivity interposed between the rail base flanges and the rail chair and contacting with said plugs, the rail base flanges wedging said strip, plugs, rails and rail chair together.

2. In a rail joint, the combination of adjacent rail ends having openings in one side of the rail base flanges, said openings merging with the outer edges of said rail base flanges, plugs of high electrical conductivity swelled into such openings, and a strip of high electrical conductivity bridging said rail base flanges and contacting with said

plugs, and a rail chair which receives the said strip and the said edges of the rail base flanges, such flanges wedging the strip, plugs, chair and rails together.

5 Signed at Montreal, Canada, this 19 day of August, 1922.

CHARLES PASCAL.
